UNITED STATES PATENT OFFICE

JAMES R. JONES AND HOWARD E. MILLER, OF JOHNSTOWN, PENNSYLVANIA

RAILROAD CROSSING INTERSECTION

Application filed December 9, 1931. Serial No. 579,961.

This invention relates to railroad rails and shapes and more particularly to railroad crossing intersections comprised of cast steel or alloy steel such as manganese steel.

3 In the manufacture of railroad crossings of cast steel or alloy steel it is highly essential to so distribute the material of the casting that internal stresses or strains incident to the cooling of the molten metal is not obtained. It is also essential that the distribution of the metal in the casting be such as to reinforce and support the structure under service conditions. Heretofore in the art 10 many structures for steel railroad crossings have been proposed but all have certain defects either in the method of manufacture employed or in the operating life and maintenance which it is one of the objects of the present invention to eliminate.

20 Another object of this invention is to provide an improved cast steel railroad crossing intersection.

Another object is to provide an improved reinforcing structure for cast steel railroad 25 crossing intersections.

Other objects and advantages will be apparent as the invention is more fully disclosed.

In accordance with the objects of the present invention we have designed a reinforced railroad crossing intersection comprised of cast steel or alloy steel, in which the reinforcement serves the double purpose of stiffening and supporting the structure against 30 load and hammer blows of passing wheels, and of providing a casting construction adapted to give an equalization in the cooling strains in the cast structure thus preventing the development of shrinkage cracks therein.

Reference should be made to the accompanying drawings wherein:—

Fig. 1 illustrates in plan view the reinforced railroad crossing intersection of the present invention;

45 Fig. 2 is a horizontal section of the same; Fig. 3 is a section along plane 3—3, Fig. 1; and

Fig. 4 is a section along plane 4—4, Fig. 1.

50 Referring to the drawings, the railroad crossing intersection shown comprises the

usual tread 1, and supporting frame including outer wall 2 having flange feet 3 and inner wall 4 having flange feet 5. Outer and inner walls are supported by transverse ribs 6 having flange feet 7.

55 In the practice of the present invention we provide curved vertical supporting ribs 8 having interiorly extending flange feet 9, the curvature of the ribs being concentric with respect to the curvature of the outer wall 2 and the size of the interiorly extending flange feet 9 being approximately identical to the size of flange feet 3 and 5 of walls 2 and 4 respectively, and spaced from wall 2 so that the rib supports the tread portion at a point 60 adjacent the intersection.

65 By this arrangement of elements in a crossing intersection the curved vertical supporting ribs afford a support for the tread portion at a point where it is most needed, and provides means to transmit the load or hammer blows of the passing wheels to all of the cross ties supporting the structure. By the provision of interiorly disposed flange feet 70 on the curved rib elements the transmission of the traffic load to the cross ties is facilitated and their position tends to counterpoise the intersection structure and to resist 75 interior displacement of the rail tread.

80 In addition due to the absence of transverse ribs and to the particular design of rib and flange feet, material shrinkage of metal during cooling is prevented and deleterious effects due to shrinkage cracks and fissures because of insufficient casting metal 85 at the tread intersection is substantially eliminated.

86 Preferably, but not necessarily, the rail intersection of the present invention is comprised of manganese alloy steel. Other steel compositions may be employed, if desired.

Having disclosed the present invention with particularity it is apparent that many modifications and departures may be made therein without departing essentially from 95 the nature and scope thereof as may be set forth in the accompanying claims.

What we claim is:

1. In a cast steel railroad crossing intersection, interiorly disposed vertical support- 100

ing ribs therefor, said ribs being curved concentrically with respect to the outer wall of said intersection.

2. In a cast steel railroad crossing intersection, interiorly disposed vertical supporting ribs therefor, said ribs being curved concentrically with respect to the outer wall of said intersection and being spaced therefrom a distance adapted to bring the supporting rib under the tread portions of the crossing at a point adjacent the intersection of the same.

3. In a cast steel railroad crossing intersection, interiorly disposed vertical supporting ribs therefor, said ribs being curved concentrically with respect to the outer wall of said intersection and being spaced therefrom a distance adapted to bring the supporting rib under the tread portions of the crossing at a point adjacent the intersection of the same, said ribs also carrying flange feet extensions, said feet extending interiorly from said outer wall.

4. In a cast steel railroad crossing intersection, interiorly disposed vertical supporting ribs therefor, said ribs being curved concentrically with respect to the outer wall of said intersection, said ribs having flange feet extensions adapted to extend interiorly therefrom.

5. A railroad crossing intersection comprised of cast steel including a base, tread portions in said base, supporting walls therefor, and interior vertical supporting rib members, said rib members being curved and disposed substantially concentric with respect to the outer wall of the intersection and spaced therefrom a distance adapted to bring the same under the tread portions at a point adjacent the intersection of the same.

6. A railroad crossing intersection comprised of cast steel including a base, tread portions in said base, supporting walls therefor, and interior vertical supporting rib members, said rib members being curved and disposed substantially concentric with respect to the outer wall of the intersection and spaced therefrom a distance adapted to bring the same under the tread portions at a point adjacent the intersection of the same, said curved rib members also carrying flange feet extensions disposed interiorly from the outer wall.

In witness whereof, we have hereunto signed our names.

JAMES R. JONES.
HOWARD E. MILLER.
